US0D1080880S

(12) **United States Design Patent** (10) Patent No.: **US D1,080,880 S**
(45) Date of Patent: ** Jun. 24, 2025

(54) **MEDICAL MONITORING DEVICE**

(71) Applicant: **Bionime Corporation**, Taichung (TW)

(72) Inventor: **Hsueh Chuan Chang**, Taichung (TW)

(73) Assignee: **BIONIME CORPORATION**,
Taichung (TW)

(**) Term: **15 Years**

(21) Appl. No.: **29/820,547**

(22) Filed: **Dec. 22, 2021**

(30) **Foreign Application Priority Data**

Jun. 30, 2021 (TW) 110303428

(51) **LOC (15) Cl.** **24-02**

(52) **U.S. Cl.**

USPC **D24/185**; D24/186

(58) **Field of Classification Search**

USPC D24/107, 183–187, 164–169

CPC G16H 10/00; G06F 1/00; G06V 10/00;
G16Z 99/00; H04L 1/00

(57) **CLAIM**

The ornamental design for a medical monitoring device, as shown and described.

DESCRIPTION

FIG. 1 is a perspective view of a medical monitoring device according to the present design;

FIG. 2 is a front view of the medical monitoring device according to the present design;

FIG. 3 is a rear view of the medical monitoring device according to the present design;

FIG. 4 is a left side view of the medical monitoring device according to the present design;

FIG. 5 is a right side view of the medical monitoring device according to the present design;

FIG. 6 is a top view of the medical monitoring device according to the present design; and,

FIG. 7 is a bottom view of the medical monitoring device according to the present design.

The broken lines in FIGS. 2, 4, 5 and 7 depict portions of the medical monitoring device that form no part of the claimed design.

1 Claim, 7 Drawing Sheets
